UNITED STATES PATENT OFFICE.

JOHN WALLACE TAYLOR, OF CINCINNATI, OHIO.

MANDREL FOR BENDING MACHINES.

Application filed September 28, 1921. Serial No. 502,702.

To all whom it may concern:

Be it known that I, JOHN WALLACE TAYLOR, a citizen of the United States, and residing at Cincinnati, Hamilton County, State of Ohio, have invented certain new and useful Improvements in Mandrels for Bending Machines, of which the following is a specification.

The present invention relates to mandrels for bending machines and particularly to mandrels utilized in bending the individual leaves of built-up leaf springs.

In the formation of leaf springs which are built up of a plurality of superposed plates to approximate a beam of uniform strength, the individual leaves are separately curved and tempered and later assembled. The leaves are usually received from the furnace in a highly heated condition and substantially straight, placed on a mandrel and bent to the proper radius of curvature, and then plunged into a cooling medium such as oil or water, while still held on the mandrel. It is essential in obtaining spring blades having proper and uniform properties that the quenching action be uniform, that is, that all parts of the spring leaf be simultaneously subjected to the cooling action of the liquid and that the liquid be free to flow over its surface throughout the quenching operation.

It has heretofore been attempted to secure by various devices the quick and uniform quenching desired by supporting the leaf so that the quenching liquid can flow freely over its surfaces. For instance, grooves have been cut diagonally in the surface of the mandrel against which the leaf rests to allow a flow of cooling liquid between the leaf and mandrel, and in another form of prior device the mandrel or master plate has had longitudinal rods mounted thereon upon which the work is supported and holes have been formed in the plate to allow the quenching liquid to flow to the under side of the work. These and other previous devices of this character have, however, not proven entirely satisfactory in operation, the physical properties of the resulting spring leaf varying along its length due to the fact that the liquid does not have free access to all surfaces of the work, and because of the formation of gas pockets adjacent the work due to poor circulation, which cause soft

spots in the metal and generally irregular results.

It has also been realized that the leaf should be cooled at approximately the same rate on both sides and in an effort to obtain this uniform rate or balanced cooling action the areas of contact of the holding means on the opposite sides of the plate have been made substantially equal, so that the surface exposed to the cooling liquid is the same in area, on both sides. This increase in area of contact between the leaf and its supports further decreases the speed of quenching.

The object of the present invention is to provide a mandrel constructed and designed to be used in the bending and quenching operation, whereby a spring leaf may be firmly held and uniformly quenched, the cooling liquid being enabled to sweep over the plate freely on both sides, the liquid flowing edgewise of the plate, thereby enabling such liquid to cool the full cross section of the metal at the same rate.

The invention may be embodied in various forms, several of which are illustrated in the accompanying drawings, in which:

Figure 1 is a front elevation, partly broken away, of a bending machine having the improved mandrel thereon.

Figs. 2, 3 and 4 are sections on lines 2-2, 3-3 and 4-4 respectively of Figure 1;

Figs. 5 and 6 are top and side elevations respectively of a modified form of mandrel;

Figs. 7 and 8 are similar views of a second modification; and

Figs. 9 and 10 are similar views of a third modification.

The improved mandrel may be used either in hand work or machine work and is, therefore, not limited to its application or use with any particular apparatus. The bending machine shown in Fig. 1 may be of any desired type but in the present instance comprises a tank 10 holding the quenching oil or water, an upright post 11 which supports at its upper end a cylinder 12, these parts being stationary and a movable cross head 13 rigidly connected to a piston 14 in cylinder 12, also a vertically movable platform 15 on which the mandrel M is supported. The platform 15 rests upon coiled compression springs 16 and is adapted to be forced downwardly into the tank by the action of the cross head and against

the action of the spring 16. Upright rods 17 guide the platform in its vertical movements and also prevent spring 16 from becoming out of alignment. To the under 5 side of the cross head 13 are secured spring members 18 between the lower ends of which extends a chain 19 which is normally maintained in a taut condition by the actions of springs 18 and which constitutes 10 in reality a flexible upper die.

The mandrel M constitutes a flexible master plate 20 having a plurality of depending ears 21 to which are pivotally secured threaded rods 22 which extend downwardly through slots 23 in platform 15 and are provided with nuts 24 by means of which the rods may be rigidly supported with their upper ends at any desired distance above the surface of the platform, 20 that is, with the master plate 20 curved to any desired radius of curvature.

A plurality of radially arranged supports or bridges 25, clearly shown in Fig. 3, are supported on the master plate 20, these 25 members being substantially rectangular but having downwardly extending spaced parallel legs 25' adapted to receive between them the plate 20. A clamping screw 26 extends through one leg of each member 25 for the purpose of securing this member to the plate 20. By loosening these screws, the members 25 may be shifted longitudinally of the plate to any desired position and, by tightening the screws, secured in such 35 position. The upper edges of the supports 25 are provided with semi-circular grooves 25'' to receive the spaced parallel, longitudinally extending rods 27, the members 25 being equal in height and rods 27 therefor 40 lying parallel to the plate 20.

Adjacent the ends of the plate 20 are secured members 28 which are similar to the supports 25 in outline and are adjustably secured to the plate 20 by screws 29 in the 45 same manner. The members 28 are provided, however, with grooves 28' deeper than the grooves 25'' of the member 25 and slots 28'' extend downwardly from these grooves for a considerable distance. The 50 provision of these slots enables the grooves 28' to be contracted transversely and for this purpose a bolt 30 is provided which extends from one end of the member 28 to the other, the tightening of the nut of this bolt 55 serving to clamp rods 27 firmly in position.

After the threaded rods 22 have been adjusted to give the plate 20 its desired curvature, rods 27 are laid in grooves 25'' and 28' of the supporting members and bolts 30 tightened so that these rods are firmly held in position. The mandrel is then ready for use. If desired, guides 31, clearly illustrated in Fig. 2, may be provided for accurately positioning the work upon the mandrel, 60 these guides being rigidly supported upon

members 32 which are adjustably secured to plate 20 by screws 33.

In the operation of the mechanism above described, a heated spring plate is taken from the furnace in its flat condition and placed upon the mandrel in the position indicated at S (Fig. 1). The piston 14 is then caused to descend so that the chain 19 contacts with the upper surface of spring S, causing its ends to bend downwardly until 75 it conforms throughout its length with rods 27. Further downward movement of the piston results in the downward movement of the mandrel and platform 15 into the oil or water contained in tank 10, whereupon 80 the liquid flows freely against and around the hot spring leaf and quickly cools the same.

When the work is cooled to the desired temperature, the piston 14 may be raised, allowing the platform 15 and mandrel to move upwardly, due to the action of the springs 16, and to allow the operator to remove the work from the machine.

When submerged, it will be seen that the 90 oil or other quenching liquid has free access to practically all of the surfaces of the work. It can not only contact with the edges but also freely flow transversely across its upper and lower surfaces, preventing the 95 formation of gas pockets and insuring the uniform and rapid cooling of the metal throughout each and every section.

The form of master plate illustrated in Figs. 5 and 6 may be substituted, if desired, 100 for that illustrated in Fig. 1. In this modification a plurality of pins 40 are secured to the master plate 20', these pins being adapted to support the work on their outer ends and to occupy a radial position for all degrees of curvature of the master plate.

In Figs. 7 and 8 the master plate 20'' has supported thereon a chain 51, the links of which are provided with points 52 which serve to support the work, but which permit 110 the free flow of liquid transversely between the body of the chain and the work. The links are rather loosely connected so that the plate 20'' may be curved as desired. In Figs. 9 and 10 a master plate 20''' is illustrated having a plurality of pins 61 secured thereto, the upper ends of the pins being grooved to receive longitudinal bars 62. These bars rest loosely in the grooves and any suitable means may be employed 120 to secure them in such position.

It will be obvious to one skilled in the art that still other modifications might be designed and that the invention is not limited to any particular form of superstructure 125 for supporting the work. It will also be apparent that the invention is susceptible of adaption to hand machines as well as to power operated machines.

Having thus described my invention, what 130

I claim as new and desire to secure by Letters Patent is:

1. A mandrel of the class described comprising, in combination, a flexible plate, and means supported on said plate constituting a superstructure for supporting an article to be bent, said supporting means comprising a series of substantially radial members of equal length, and longitudinal bars supported on the outer ends of said members and adapted to receive the work.
2. A mandrel of the class described comprising, in combination, a flexible plate, and means supported on said plate constituting a superstructure for supporting an article to be bent, said supporting means including a plurality of rods arranged in parallel spaced relation to the plate, and means for supporting said rods on said plate and adapted to maintain said rods in parallel spaced relationship to the plate for all curvatures which may be imparted to said plate.
3. In a bending and quenching machine, in combination, a work supporting mandrel comprising a flexible plate and a superstructure supported thereon for supporting the work, said superstructure being constructed and designed to permit the free flow of liquid transversely between the work and the flexible plate, and a flexible die adapted to cooperate with said mandrel to bend the work and retain the same in place during quenching, said die being constructed and designed to allow free flow of liquid transversely across the work on the side opposite the mandrel.
4. In a mandrel, a master plate and a superstructure therefor, comprising in combination, a plurality of spaced parallel rods and means for connecting and supporting said rods in spaced parallel relation to the master plate.
5. In a mandrel, a flexible master plate and a superstructure for the master plate comprising a work supporting member and means for supporting said member on and in spaced relation to the master plate.
6. In a mandrel, a flexible master plate and a superstructure therefor comprising a work supporting member and means including a plurality of members normal to the plate for maintaining and connecting said work supporting member in spaced relation to the plate.
7. In a mandrel, a flexible master plate and a superstructure therefor comprising a work supporting member and means including a plurality of members adapted to be detachably and adjustably secured to the plate for maintaining said work supporting member in spaced relation to the plate.

In testimony whereof I hereunto affix my signature.

J. WALLACE TAYLOR.
